UNITED STATES PATENT OFFICE

MARSHALL S. FIELD, OF DAVENPORT, IOWA, ASSIGNOR OF FORTY PER CENT TO CHARLES H. SUITER AND TWENTY PER CENT TO JOHN C. MOHL, BOTH OF DAVENPORT, IOWA

AIR CLEANER

Application filed June 26, 1926. Serial No. 118,699.

This invention relates to new and useful improvements in air cleaners generally, although the invention is more specifically intended for use in connection with internal combustion engines.

Amongst the several objects of the invention are to provide a device for removing foreign matter from the atmospheric air prior to said air entering the carburetor; to provide an air cleaner attachment for internal combustion engines which may be connected to the crank case of the engine and to the air inlet of the carburetor whereby air will be caused, by the suction of the carburetor, to circulate through the crank case and thereby maintain the engine at a cooler temperature, and also eliminate condensation in the crank case; to provide for the air circulation through the crank case for carrying off the chemical gases which are injurious to the engine, and to direct said chemical gases from the crank case through the carburetor to the explosive cylinders where they are burned and whereby both increased power and increased gasoline mileage is obtained.

Another object of the invention lies in the provision of a cleaning device which restricts the suction from the crank case and thereby prevents the withdrawal of any of the oil therefrom, in combination with means for admitting a varied quantity of atmospheric air to the carburetor whereby a sufficient quantity of air can be supplied thereto.

With these and other objects in view which will more fully appear the nature of the invention will be more clearly understood by following the description, the appended claims, and the several views illustrated in the accompanying drawings, in which

40 Figure 1 is a side elevation of an internal combustion engine equipped with my invention,

45 Figure 2 is an enlarged top plan view of the air cleaning device,

50 Figure 3 is a longitudinally sectional view taken on the line 3—3 of Figure 2, and

Figures 4, 5, 6, 7 and 8 are transverse sectional views taken on the corresponding lines of Figure 3.

55 Like numerals designate corresponding

parts throughout the several figures of the drawings.

Referring to the drawings in detail, I have shown an internal combustion engine A having the usual crank case B equipped with the 55 usual air inlet or breather pipe 5 and a carburetor C and intake manifold D associated with the engine in the usual manner, said carburetor including an air inlet 6.

My improved air cleaning device E includes a sheet metal drum which is formed from a plurality of nested cups or cup-shaped sections which respectively include walls 7^a, 8^a, 9^a, 10^a, 11^a and 12^a, and peripheral flanges 7^b, 8^b, 9^b, 10^b, 11^b, and 12^b connected to said 60 walls. Each flange is formed with an offset 13 at its outer edge to form a seat 14 to receive the adjacent cup. The outer end of the cup 7 is closed by a wall 15. Thus, the cups form a series of adjacent air compartments for a 65 purpose as will hereinafter appear. In order to secure these cups in assembled relation, I have employed a longitudinally extending bolt 16 which passes through aligned openings 17, 18, 19, 20, 21, 22 and 23 eccentrically 70 formed in the walls of the cups. The cup 7 is formed with a rearwardly extending air inlet nipple 24 to which one end of a flexible piping 25 is connected, the other end 26 of said piping fitting within an opening which 75 communicates with the crank case at a point farthest removed from the air inlet or breather pipe 5. The wall 12^a of the opposite cup 12 is provided with an air outlet nipple 27 which is connected to the inlet 6 of the carburetor C. The walls 7^a, 8^a, 9^a, 10^a and 11^a, of the cups 7, 8, 9, 10 and 11 respectively are 80 formed with staggered openings for causing air to be baffled and to partake of a spiral passage during its travel through the drum. 85 To this end, the wall 7^a of cup 7 is provided with an opening 28, the wall 8^a of cup 8 is provided with a pair of openings 29—29, the wall 9^a of cup 9 being provided with openings 30—30, the wall 10^a of cup 10 being provided with openings 31—31, and the wall 11^a of cup 11 being provided with openings 32—32. It will be noticed that the openings 90 28, 29, 30, 31 and 32 are arranged in different radial planes, and that no two of the 95

100

openings are arranged in longitudinal alignment and consequently the air is forced to move in a spiral path through the successive cups or sections.

5 By reason of the bolt 16 being eccentrically positioned, all of the cups will be necessarily obliged to partake of their proper positions in order to be assembled.

The diameter of the air inlet nipple 24, 10 as well as the diameter of the air inlet pipe 25, is larger than the diameter of the single opening 28 in the wall 7^a of the cup or section 7. By providing a single opening in the wall 7^a and having this opening of an area 15 smaller than the diameter of the pipe 25 or the inlet 24, I have prevented the suction from withdrawing any of the oil from the crank case. The opening 28 being restricted in its area is too small to permit the desired quantity 20 of air to be directed to the carbureter. Consequently, I have provided a variable inlet in the drum E for atmospheric air. Preferably this inlet consists of three openings 33, 34, and 35 which are respectively formed in 25 the peripheral wall 8^a of the section 8. Associated with this section is a sleeve valve 36 having a plurality of openings 37, 38 and 39 adapted to respectively register with the openings 33, 34 and 35. A set screw 40 is 30 carried by the sleeve 36 for engagement with the peripheral wall 8^b of the section 8 so as to secure the valve in any desired position of adjustment.

In operation, air passes into the air inlet 35 or breather pipe 5 of the crank case, through said crank case to the pipe connection 25, and thence through the air cleaner drum E, to the carbureter C. This air as it passes through the drum is caused by the baffles to 40 partake of a spiral passage and oil vapors from within the crank case are carried by the air into the cleaning drum. These oil vapors are caused to be filmed onto the walls or baffles 8^a, 9^a, 10^a, and 11^a, the spiral direction 45 of movement of the air causing the oil vapors to be spread fairly uniformly over the surfaces of the baffles. As a result of the oil films on the baffles, all foreign matters carried into the drum by the air which is received 50 from the crank case and also from the atmosphere, will be collected by said oil films on the baffles and thereby prevented from being transmitted to the carbureter. The amount of foreign matter collected from the 55 air and deposited on the successive baffles will be successively reduced in amount so that the air, when it reaches the carbureter, will be clean. It will be noted that the air as it passes through the crank case will be heated; that the air thus circulating through the crank case 60 will maintain the engine at a cooler temperature; that by reason of air circulating through the crank case, any water contained in the crank case oil will be 65 prevented from freezing and consequently

condensation in the crank case will be eliminated; that chemical gases will be carried from the crank case through the carbureter to the explosive cylinders, and consequently both increased power and increased gasoline mileage will be obtained, and that the heated air from the crank case will be mixed in the drum with atmospheric air whereby the carbureter will be always supplied with warm clean air.

It is of course to be understood that the details of structure and arrangements of parts may be variously changed and modified without departing from the spirit and scope of my invention.

I claim:

1. In an air cleaner, the combination with a drum formed of a plurality of inter-engaging cup-shaped sections and having at one end an inlet adapted for attachment to the crank case of an internal combustion engine and having at its other end an outlet adapted for connection with the carbureter thereof, a baffle within the drum and having an opening of less area than the area of said inlet, an atmospheric air inlet formed in one of the sections between the baffle and said outlet, and a sleeve valve rotatably mounted on said section for cooperation with the opening thereof.

2. In air cleaning means, a drum formed of a plurality of cup-shaped sections assembled end-to-end and interfitting in a manner for centering the sections in coaxial alignment and providing spaced exterior annular flanges, means to secure the sections together, said drum having an inlet and an outlet and spaced baffle walls and an air inlet intermediate of the inlet and outlet, and a movable sleeve valve on the drum in association with the air inlet and guided by a spaced pair of the annular flanges.

3. In air cleaning means, a drum formed of a plurality of cup-shaped sections assembled end-to-end and interfitting in a manner for centering the sections in coaxial alignment and providing spaced exterior annular flanges, means to secure the sections together, said drum having an inlet and an outlet and spaced baffle walls and an air inlet intermediate of the inlet and outlet, a movable sleeve valve on the drum in association with the air inlet and guided by a spaced pair of the annular flanges, and means to secure the sleeve valve at adjusted positions.

4. In an air cleaner, the combination with a drum formed of a plurality of cup-shaped sections and having at one end an inlet adapted for attachment to the crank case of an internal combustion engine and having at its other end an outlet adapted for connection with the carbureter thereof, a baffle within the drum and having an opening of less area than the area of said inlet, and an atmos-

pheric air inlet formed in one of the sections between the baffle and said outlet.

5. In an air cleaner, the combination with a drum formed of a plurality of annular flanged cup-shaped sections and having a lateral inlet and an axial outlet for attachment with the crank case of an internal combustion engine and the carbureter thereof respectively, a plurality of baffles disposed within the drum and respectively formed with openings arranged to cause the air to partake of a spiral travel during its passage through the drum, and an atmospheric air inlet formed in the drum between one of the baffles and the outlet.

15. In an air cleaner, the combination with a drum formed of a plurality of interengaging annular flanged cup-shaped sections and having a lateral inlet and an axial outlet for attachment with the crank case of an internal combustion engine and the carbureter thereof respectively, a plurality of baffles disposed within the drum and respectively formed with openings arranged to cause the air to partake of a spiral travel during its passage through the drum, atmospheric air inlets formed in the drum between one of the baffles and the outlet, and a sleeve valve rotatably mounted upon the drum for cooperation

30 with said atmospheric air inlets.

7. In an air cleaner, the combination with a drum formed of a plurality of interengaging cup-shaped sections and having at one end an inlet adapted for attachment to the 35 crank case of an internal combustion engine and having at its other end an outlet adapted for connection with the carbureter thereof, a baffle within the drum and having an opening therein, an atmospheric air inlet formed 40 in one of the sections between the baffle and said outlet, and a sleeve valve rotatably mounted on said section for cooperation with the opening thereof.

In testimony whereof I hereunto affix my
45 signature.

MARSHALL S. FIELD.
